his Attorney.

UNITED STATES PATENT OFFICE.

WILLIAM ANDLER, OF CHICAGO, ILLINOIS.

DOOR CONSTRUCTION.

Application filed February 27, 1925. Serial No. 11,913.

My invention relates to improvements in door constructions, more particularly to automobile door constructions, and the main object of my invention is the provision of means through the agency of which to prevent the warping of doors or to effect the straightening of doors after such warping has occurred.

Other objects will appear hereinafter.

10 The invention consists in the combinations and arrangements of parts hereinafter described and claimed.

15 The invention will be best understood by reference to the accompanying drawings forming a part of this specification, and in which,—

20 Fig. 1 represents a fragmental elevation of the interior of a motor vehicle, illustrating in particular the application of my improvements to the vehicle door;

Fig. 2 represents a top view of the parts shown in Fig. 1;

25 Fig. 3 is a vertical sectional view taken approximately on the line 3—3 of Fig. 2;

25 Fig. 4 is a fragmental elevation showing a modified form of construction in which the straightening means is applied entirely to the same wall of the door;

30 Fig. 5 represents an enlarged horizontal section taken approximately on the line 5—5 of Fig. 4; and

Fig. 6 represents a side elevational view of a door provided with the modified form of construction illustrated in Fig. 4.

35 The accompanying drawings illustrate the preferred embodiments of my invention in which 7 denotes a vehicle door which is secured at its forward edge 8 by the hinges 9 to the body 10 of the vehicle, the free rear edge 11 of the door being located rearwardly of the forward end of the seat structure 12, all in accordance with the door construction found in well known types of motor vehicles.

40 In this construction, the door 7 comprises an outer wall 13, made preferably of metal, and an inner wall or side 14 which may consist of any suitable material customarily employed for the purpose, the same being supported upon the bottom offset rail or

45 piece 15 of the front wall and upon the reinforcing member 16 attached to the top rail or piece 17 of the front wall. Under this construction, my improvements consist preferably of a holder member 18 which is welded or otherwise secured to the inner face of the outer wall 13, the said holder

member having an outwardly inclined boss portion 19 in which is threaded a rod 20 having an outwardly offset portion 21 that extends through an aperture 22 provided in the inner wall 14 and thence has a threaded region 23 to which is applied a turn buckle 24. 25 represents a bracket member which is formed with leg portions 26 designed to suitably straddle the door locking lever 27, the said bracket member having an outstanding boss 28 which is directed inwardly and in which is threaded a rod 29 to connect with the turn buckle 24. The truss construction thus provided is applied along the free edge 11 of the door 7, and in this construction, it will be observed that the opening 22 in the inner wall 14 comes above the seat 12 so that the rod connection between the holder member 18 and turn buckle 24 will not conflict with said seat. The bracket member 25 is preferably secured to the reinforcing element 16 by means of bolts as 30 and securing nuts 31 for said bolts. Formed also with the bracket member 25 along the rear side thereof is an extension 31 having a vertical opening or bore 32 therein for the securement of the rod 33 employed as one of the supports for the curtain 34 which constitutes part of the covering for the vehicle and comes immediately above the door. By providing the rod receiving opening 32 the curtain 34 may be readily secured to the bracket member when the door is closed, and may as readily be detached when the door is to be opened. In connection with the extension 31 I preferably provide a bore 35 in which is threaded a plug 36. 37 is a finger piece attached to a stem 38 which extends through the plug 36 and bore and into the bore 32 for impingement on the curtain rod 33. Said stem 38 is normally thrust into position to engage the curtain rod by a spring 39 which is imprisoned in the bore 35 to act on a collar 40 attached to said stem.

45 In the form of construction shown in Figs. 4 and 6 the door is of the type that is hinged to the body of the car along its rear edge 41, the front edge 42 thereof being the free edge. In the use of this type of door, where the seat is distant from the free edge 42, I preferably apply both the holder member 18 and the bracket member 25 to the same face of the inner wall 43 of the door, there being a straight, non-offset rod 44 employed in this construction to connect the holder

member 18 with the turn buckle 24. In this construction, however, as in the previous construction, it will be understood that due to the outward inclination of the portion 19 5 on the holder member and to the inward inclination of the boss 28 of the bracket member the rods associated therewith and adjustably connected by the turn buckle member are angularly inclined with respect to the 10 door in order either expansively or contractably to exert a thrust or pull for straightening the door.

While I have illustrated and described the preferred form of construction for carrying 15 my invention into effect, this is capable of variation and modification without departing from the spirit of the invention. I, therefore, do not wish to be limited to the precise details of construction set forth, but 20 desire to avail myself of such variations and modifications as come within the scope of the appended claims.

Having described my invention, what I claim as new and desire to secure by Letters 25 Patent is:

1. The combination with a door having a plurality of walls, of a truss construction comprising bracket members attached to separate walls of the door, and a rod connecting said members, substantially as described.

2. The combination with a door having a plurality of walls, of a holder member attached flat to one wall of the door, a bracket member attached flat to a separate wall of 30 the door at a point distant from the holder

member, and an adjustable member connecting said holder member with said bracket member, substantially as described.

3. The combination with a vehicle door 40 constructed with double walls, a holder member attached to a face of one wall, a bracket member attached to a face of the other of the walls, and adjustably connected members connecting said holder member 45 with said bracket member, substantially as described.

4. The combination with a vehicle door constructed with double walls, a holder member attached to the inner face of one wall, 50 a bracket member attached to the outer face of the other of the walls, and adjustably connected members connecting said holder member with said bracket member, one of said adjustably connected members extending 55 through the wall to which the bracket member is attached, substantially as described.

5. In a vehicle, the combination with a hinged door and a curtain arranged over 60 said door, of a truss construction applied to the hinged door adjacent to the free edge thereof and affording an application of force to keep the door from warping, an extension on said truss construction, and a rod 65 for holding the curtain detachably engaged with said extension, substantially as described.

In testimony whereof I have signed my name to this specification.

WILLIAM ANDLER.
